SURGE ARRESTOR

George W. Reznor, Mercer, Pa., assignor to International Telephone and Telegraph Corporation, a corporation of Maryland

Filed Jan. 29, 1964, Ser. No. 341,040

3 Claims. (Cl. 138—30)

This invention relates to devices for arresting surges in the pressure of a fluid delivered by a pump or the like, and has particular reference to a surge arresting device which can be simply and readily connected into a pressure line carrying a pulsing fluid.

The device according to the present invention finds a particular application in smoothing out the pulses resulting from the output of a high pressure pump, such as may be employed to deliver fuel oil to a burner. In such application the device has the function of eliminating burner pulsation.

The device according to the present invention consists of a long nipple having end caps defining a casing enclosing a capsule formed of an envelope containing a quantity of compressible gas such as Freon R-13. The end caps are provided with suitable structure for inserting the assembly into the pressure line. The envelope containing the compressible gas is rolled upon itself within the nipple in such a manner as to leave a passage therethrough offering no impedance to the flow of the pressure fluid, and at the same time presenting a large compliant surface for the absorption of the pressure pulses.

With the foregoing considerations in mind it is a principal object of this invention to provide an improved surge arrestor adapted to be connected into a pressure line having a pulsating column of liquid moving therein, for the purpose of smoothing out the pulsations in the line, such surge arrestor being characterized by a gas filled envelope folded or coiled upon itself and presenting a large compliant surface to the pulsing fluid column, and offering no substantial impedance to the flow of the pressure fluid.

Other objects and important features of the invention will be apparent from a study of the following specifications taken with the drawing, which together describe and illustrate a preferred embodiment of the invention, and the best mode of practicing the principles thereof. Other embodiments may be suggested to those having the benefit of the teachings herein, and such other embodiments are intended to be reserved especially as they fall within the scope and purview of the subjoined claims.

In the drawing:

FIG. 1 is an elevational view of a surge arrestor embodying the improvements according to the present invention;

FIG. 2 is a longitudinal sectional view through the surge arrestor seen in FIG. 1;

FIG. 3 is a transverse section taken along the line 3—3 of FIG. 2, looking in the direction of the arrows;

FIG. 4 is a perspective view showing a portion of an envelope adapted to enclose a quantity of compressible gas; and

FIG. 5 is an end view of the envelope seen in FIG. 4.

Referring now to the drawing, the improved surge arrestor according to the present invention is referred to generally by the reference numeral 10, and includes a hollow cylindrical member or nipple 11 which is threaded at each end as at 12 and 13. Respective knurled closures 14 and 16 are adapted to be threaded to the member 11, and each of the closures 14 and 16 is drilled and tapped at 17, so that the assembly thus far described can be connected into a pressure line 18.

The hollow cylindrical body member has its internal

2

diameter substantially larger than the internal diameter of the pressure line 18, and the hollow body member or nipple 11 is adapted to enclose a compliant capsule indicated generally by the reference numeral 20. Capsule 20 consists of a pair of sheets 21 and 22 made of membranes or film material cemented or heat sealed along their margins 23. For example, material from which the sheets 21 and 22 may be made is nylon or the like. Prior to the final sealing of the capsule 20 along its edges 23 a quantity of a compressible gas such as Freon R-13 is placed therein. In the embodiment shown in the several views herein approximately 43 cc. of Freon R-13 is inserted into the capsule 20. In such example, the capsule is formed by two 1/2" x 5" pieces, each being approximately .003" in thickness. The nipple member 11 for such size of capsule 20 may be of the order of approximately 6" in length, with an inside diameter of 1".

As seen particularly in FIG. 3, the capsule 20 formed as described is folded or coiled upon itself so as to leave in such folding or coiling a lengthwise passage 24 posing substantially no restriction or impedance to the flow of the pulsating column of liquid. The gas within the capsule 20 is indicated by the letter G, and the pulsing of the liquid column within the body member 11 causes the capsule 20 to alternately compress and expand to smooth out the pulsations within the pressure fluid.

The invention has been described in terms of a preferred embodiment thereof, but the scope thereof is intended to be limited only by the claims here appended.

I claim:

1. A surge arrestor adapted to be connected in a pressure line conducting a column of pulsating liquid for smoothing out the pulses in said column of liquid, said arrestor comprising a casing defined by a substantially hollow cylindrical member having an internal diameter substantially larger than the internal diameter of said pressure line, means closing the ends of said casing and affording means for connecting said casing into said pressure line with the longitudinal axis of said casing extending coincident with the axis of said pressure line, and a yielding capsule contained within said casing for absorbing the pulses of said column of liquid, said capsule being formed of a pair of spaced apart compliant membranes joined in spaced apart sealed relationship and having a quantity of compressible gas held therebetween, said capsule being coiled upon itself and confined in said coiled condition by the said casing and presenting in such coiled condition a passage for movement of said pulsing column of liquid and a large compliant surface to said liquid.

2. A surge arrestor adapted to be connected in a pressure line conducting a column of pulsating liquid for smoothing out the pulses in said column of liquid, said arrestor comprising a casing defined by a substantially hollow cylindrical member having an internal diameter substantially larger than the internal diameter of said pressure line, means closing the ends of said casing and affording means for connecting said casing into said pressure line with the longitudinal axis of said casing extending coincident with the axis of said pressure line, and a yielding capsule contained within said casing for absorbing the pulses of said column of liquid, said capsule being formed of a pair of spaced apart compliant membranes having a quantity of compressible gas held therebetween, said capsule being coiled upon itself and confined in said coiled condition by the said casing and presenting in such coiled condition a passage for movement of said pulsing column of liquid and a large compliant surface to said liquid.

3. A surge arrestor adapted to be connected in a pressure line conducting a column of pulsating liquid

for smoothing out the pulses in said column of liquid, said arrestor comprising a casing defined by a substantially hollow cylindrical member having an internal diameter substantially larger than the internal diameter of said pressure line, means closing the ends of said casing and affording means for connecting said casing into said pressure line, and a yielding capsule contained within said casing for absorbing the pulses of said column of liquid, said capsule being formed of a pair of spaced apart compliant membranes and having a quantity of compressible gas held therebetween, said capsule being coiled upon itself and confined in said coiled condition by the said casing and presenting in such coiled condition a

5 passage for movement of said pulsing column of liquid and a large compliant surface to said liquid.
